CLAIM

The ornamental design for a magnetic back parts storage container, as shown and described.

DESCRIPTION

FIG. 1 is a front elevational view of a magnetic back parts container, showing my new design;

FIG. 2 is a rear elevational view thereof;

FIG. 3 is a left side elevational view, the right side being a mirror image thereof;

FIG. 4 is a bottom plan view thereof;

FIG. 5 is a top plan view thereof; and,

FIG. 6 is a perspective view thereof, the broken line showing of parts inside the container is for illustrative purposes only and forms no part of the claimed design.

FIG. 6
